EYE SHIELD

Marie Loos, Fort Wayne, Ind.

Application October 2, 1950, Serial No. 187,897

3 Claims. (Cl. 128—163)

1
My invention relates to improvements in eye shields, pads or the like, and is designed for use not only when a sun bath is to be taken, but also when it is desired to rest the eyes.

The present application is a continuation-in-part of my prior application Serial No. 793,262, filed December 22, 1947 and allowed July 27, 1950, now Patent No. 2,527,947.

Shields or pads have been heretofore proposed for protecting the eyes when taking a sun bath, artificial or otherwise. Also compresses consisting of wads of cotton or cloth moistened with witch hazel, eye lotion or water have been used upon the closed eye to rest and refresh same. However, such expedients are objectionable on a number of scores.

In the first place, such prior art eye shields have required adhesive strips to secure them in place; or they have been spectacle-like in form with a nose bridge and the equivalent of temple bars for keeping them in place. Such expedients leave white streaks or areas, thus preventing the user from getting an even sun tan. And wads of cloth or cotton covering as they do a considerable area of the face adjacent the eye are similarly objectionable.

It is therefore the primary object of my invention to overcome the objections noted and provide eye pads or shields which, while composed of fabric or other kindred material, so as to be flexible and conform to the shape of the closed eye, will nevertheless remain in place without resorting to adhesive strips or a spectacle-like holding frame.

More specifically stated, the invention contemplates a flexible pad or shield which is preferably largely composed of fabric or fabric-like material and which, partly by reason of its shape and partly by reason of a multiple ply body formation, will, when wetted, conform to the contour of the eyeball and thereafter retain such shape so as to remain in place upon the closed upper lid even when a stiff wind is blowing.

It is a further object of the invention to provide a flexible multiple ply pad or shield for the purpose specified having an outer shape-defining and retaining ply which is exposed to the sun, and which outer ply is of a more closely woven fabric such as velvet and less pervious to moisture than is the inner eyelid-contacting ply, whereby the medicated or other solution with which the pad is saturated will mainly evaporate through the lid-covering ply of the pad to cool the user's eyes. The outer or shape-defining ply can be given the characteristics noted by applying thereto a layer

of plastic or plastic-adhesive which may be availed of for securing adjacent plies together.

Still another object of the invention is to provide a device as characterized which includes an outer sun ray-absorbing or deflecting ply, preferably a black velvet fabric, and an eyelid-contacting moisture-holding ply, preferably of white velour fabric, and an intervening plastic or originally adhesive ply for not only securing the aforementioned plies together but for substantially preventing moisture transmission from one to the other, and, further, for assisting in maintaining the shape of the pad to conform to the lid-covered eyeball after the pad had been wetted and put in place.

Other objects and advantages of the invention will become apparent as the description proceeds, reference being had to the accompanying drawing which illustrates the now preferred example of the invention.

It is to be understood, however, that my inventive concept is susceptible of other mechanical expressions within the spirit and scope of the subject matter claimed hereinafter.

25 In the drawing, wherein the same reference characters have been used to designate the same parts throughout the several views—

Fig. 1 is a perspective view illustrating one form of the pads in use;

30 Fig. 2 is a perspective view illustrating the invention including an inner lid-contacting moisture-retaining ply, an outer sun ray-intercepting ply, and an intermediate ply of plastic, and initially adhesive waterproof material for securing the inner and outer plies together;

Fig. 3 is a cross-sectional view through the form of invention illustrated in Fig. 2; and

Fig. 4 is an exploded view of the eye pad.

Referring to the drawings, the pad **10** is shown **40** as comprising an inner eyelid-contacting ply **11** of soft absorbent material such as a heavy napped white velour, which is relatively loosely woven and capable of absorbing liquid. This heavy napped material, when wetted, has a tendency **45** to cling to the eyelids.

The outer ply **12** is preferably of a closely woven material such as, for example, black or colored velvet, satin, or broadcloth, the use of such a dark outer ply being impervious to sun rays and **50** protecting the eyes and eyelids of the user from the harmful effect of the sun rays. The plies **11** and **12** are secured together by an intermediate thin ply of plastic, initially adhesive material **13**.

The plies **11** and **12** are shaped as illustrated in Figs. 1 and 2 and may be stamped or cut out

from a sheet by a stamping process in which a cutting die of proper shape is employed.

The plastic ply 13 not only serves to secure the inner and outer plies 11, 12 together, but also prevents outward evaporation of the moisture from the inner ply 11 through the outer ply 12. And, additionally, of course, the ply of plastic 13 serves to give the pad a certain amount of stiffness or "character," so to speak, so that when having been wetted it will tend to conform to the shape of the lid-covered eyeball and retain such shape so as not to be blown off by a gust of wind. The plastic ply 13 also intercepts light rays and prevents passage of same to the inner 15 ply 11, although permitting heat generated by the light rays to be transmitted to the inner 11.

If the pads are used for an extended period at a time, it is preferable that they should be periodically wetted.

Practical use of these pads over a long period of time has demonstrated their characteristics of remaining in place even in a strong wind. And, as earlier mentioned herein, the use of my pads avoids leaving white marks on the face surrounded by sun tan, as would be the case where adhesive strips or spectacle temple bars or the like are used for retaining the pad in place.

Having thus described my invention, what I claim is:

1. An eye shield comprising a flexible multiple ply pad consisting of an outer sheet of a relatively closely woven fabric which is relatively impervious to sun rays and moisture and is heat absorptive, an inner sheet of a relatively loosely woven tufted fabric, said inner sheet being porous to permit medicament or water which has been applied to said sheet to travel therethrough to the eyelid, means securing the fabric sheets together into contiguous engagement with one another, said shield having an upper convex contour and a lower concave contour and being rounded at its respective sides, said shield when moistened being adapted to be placed on the closed eyelid and conform to the shape thereof and further adapted to be confined within the bony conformation of the orbital area whereby the edges of the pad lie substantially within and adjacent the outline of the orbital area to thereby prevent dislodgement of the shield by air currents.

50

2. An eye shield comprising a multiple pad consisting of an outer sheet of a relatively closely woven fabric which is relatively impervious to sun rays and moisture and is heat absorptive, an inner sheet of a relatively loosely woven tufted fabric which is porous to permit medicament or water which has been applied thereto to deposit the same on the eyelid, a layer of adhesive interposed between the outer and inner sheets to unite the same and provide a yielding stiffening property to the pad and further preventing moisture applied to the inner fabric from passing to the outer fabric layer, said shield having an upper convex contour and a lower concave contour and being rounded at its respective sides, said shield when the inner ply is moistened being adapted to be placed on the closed eyelid and conform to the shape thereof and further adapted to be confined within the bony conformation of the orbital area whereby the edges of the pad lie substantially within and adjacent the outline of the orbital area to thereby prevent dislodgement of the shield by air currents.

3. An eye shield comprising a flexible multiple ply pad consisting of an outer sheet of velvet fabric which is relatively impervious to sun rays and moisture and is heat absorptive, an inner sheet of a relatively loosely woven heavy napped tufted fabric which is porous to permit medicament or water which has been applied thereto to deposit the same on the eyelid, a layer of adhesive interposed between the outer and inner sheets to unite the same and provide a yielding stiffening property to the pad and further preventing moisture applied to the inner fabric from passing to the outer fabric layer, said shield having an upper convex contour and a lower concave contour and being rounded at its respective sides, said shield when the inner ply is moistened being adapted to be placed on the closed eyelid and conform to the shape thereof and further adapted to be confined within the bony conformation of the orbital area whereby the edges of the pad lie substantially within and adjacent the outline of the orbital area to thereby prevent dislodgement of the shield by air currents.

MARIE LOOS.
